(57) **CLAIM**

The ornamental design for a sink, as shown and described.

DESCRIPTION

In a preferred embodiment, the nature of this product is as a plumbing fixture primarily useful for washing various objects.

FIG. 1 is a right, top, front perspective view of a sink according to my new design;

FIG. 2 is a top plan view thereof;

FIG. 3 is a front elevational view thereof, the rear elevational view thereof being a mirror image of the front elevational view shown;

FIG. 4 is a right side elevational view thereof, the left side elevational view thereof being a mirror image of the right side shown; and,

FIG. 5 is a bottom plan view thereof.

The broken line representations of drain structure in the figures and mounting holes in FIGS. 1, 2 and 5 are for the purpose of illustration only, and form no part of the claimed design.
